SUSPENDING MEANS FOR HARNESS FRAMES

Paul C. Consoletti, Milford, Mass., assignor to
Draper Corporation, Hopedale, Mass., a corpora-
tion of Maine

Application March 3, 1950, Serial No. 147,473

10 Claims. (Cl. 139—88)

1

This invention pertains to improvements in connecting means for use in attaching harness cords to harness frames such as are employed in looms for weaving.

It is an object of the invention to devise an improved and simplified attaching means for use in attaching any of the various types of loom harness mechanisms to harness frames and to devise relatively simple, inexpensive and yet effective means which shall perform its intended function without more than a minimum of effort in assembly, adjustment or maintenance and without any tendency to become displaced once it has been definitely positioned.

In the conventional loom two or more harness frames are employed for supporting a relatively great number of heddles through each of which one of the warp threads is passed and by which it is manipulated during the shedding of the warp incidental to carrying out the weaving function. These frames take various forms, but each is reciprocated throughout a range of a few inches by harness mechanism, so-called, which must be attached to the frame in some positive manner. Generally such harness mechanism comprises, among other elements, a system of cords or straps which are attached to the frames by some connecting means a great many different forms of which have been employed, but all of which have definite limitations. In harness frames, especially those fabricated from metal, it is frequently the practice to extrude or otherwise form the top and bottom frame rails in such manner that a beaded rib is provided to which the straps or cords of the harness mechanism are connected by an attaching or connecting means. It is this general type of harness mechanism and frame with which the present invention is concerned and for which the attaching means herein described and claimed is adapted to be utilized.

The invention essentially comprises opposed clamping members which are easily and quickly, although very positively, attached to the beaded rib of the frame rails and at the same time, are adapted to clamp or otherwise retain a looped connecting means to which the harness cords or straps are hooked or otherwise connected.

The invention will hereinafter be described by reference to the accompanying figures of drawing in which a preferred embodiment and one modification of the invention have been illustrated, and wherein:

Fig. 1 is an elevational view showing a harness frame to which the connecting means of the instant invention have been applied.

2

Fig. 2 is a perspective view, certain parts being shown exploded, and further illustrating the details of a preferred form of the invention.

Fig. 3 is a detail view showing a modification.

Now referring to Fig. 1, a harness frame is comprised of top and bottom rails generally indicated by numerals 10 and 11 and being connected at each end to end struts 12 and 13, these four frame members preferably being attached at the corners by rivets, although the exact mode of fabrication of the parts and the means by which they are interconnected forms no part of the present invention and naturally several other types of construction may be used if desired. The rails 10 and 11 support heddle carrying bars 14 and 15 which are preferably formed as elongated, thin strips of hardened steel and which are quickly removable and which may be replaced and locked in position by a quickly releasable means one of which is shown at each of the ends of the bars 14 and 15 and which are designated by the numeral 16.

A plurality of heddles 17 are threaded onto these bars 14 and 15 and are free to slide along the length thereof within limits as defined by the extent of the frame width and as governed by the number of heddles which may be carried within any particular frame. The details of the heddle frame per se need not be explained more thoroughly here since they are the subject matter of application Serial No. 144,972, filed February 18, 1950, now U. S. Patent 2,618,296, and a full disclosure is to be found there. Furthermore, it is not important as to what particular form the frame details take except in that it is desirable that each of the rails 10 and 11 be provided with a beaded rib 18 or 19 throughout a part or all of its length. One of these beaded ribs is shown more clearly in Fig. 2, the rib portion extending from a hollow rectangular tubular extrusion or similar pressed or rolled form and being enlarged so that a somewhat cylindrical bead 20 is presented along the entire length of the rail for facilitating the attachment of the harness connecting means.

The preferred form of the invention, Fig. 2, comprises two opposed clamp members 21 and 22 which are preferably identical in form. Each one of these clamp members is provided at one side of its vertical center line with a hole 23 for reception of a clamping or retaining screw 24, said hole being countersunk in the event the screw or other connecting means is of a type to require that. The other side of the clamp member 22 is drilled and tapped as at 25 for the reception of

the threaded end of the screw or other connecting means 24'. Thus since these drilled and tapped holes are at opposite sides of the center line and are symmetrically disposed, the identical parts when opposed as herein shown may be interconnected by two screws, although it is to be understood that bolts and nuts may be used if desired in which event neither of the holes need be tapped. However, it is preferably that screws with countersunk heads be used since that leaves a smooth exterior to the connecting means and therefore there is no conflict or undesired interengagement between parts of adjacent harness frames, it being understood that these frames are relatively thin and that in looms adapted to weave patterned fabric, a number of said frames are employed and confined to a relatively narrow space.

The clamp members 21 and 22 are provided with grooves 26 and 27, respectively, which engage or embrace either side of the bead 20 thereby to retain the connecting means at any desired fixed position along the length of the frame rails, it being the general practice to employ four such connecting means, two above the harness frame and two below it. Each of the clamp members is vertically grooved as at 28 for the reception of a threaded sleeve 29, this threaded sleeve 29 fitting part in each of the clamp members and also having at its lower end a means for preventing its withdrawal once the members have been firmly attached to the bead 20, and also for preventing rotation of the sleeve. This last means comprises a flange or other abutment 30 which is flattened as at 31 on at least one side and preferably both sides, so that the abutment engages in recesses 32 one of which is preferably provided in each of the clamp members since they are substantial duplicates. The flattened sides prevent rotation of the sleeve while the flange portion or abutment 30 prevents axial movement of the sleeve, that being essential since considerable axial pull is exerted on the connecting means as the harness frames are rapidly reciprocated to and fro during weaving.

A looped connecting means having a threaded stem or shank 33 and a hooked or looped end 34 is threaded into the sleeve 29, the threaded interconnection between the two serving as a means for adjusting the frame, although it is generally to be understood that other adjusting means is also provided in the harness itself so that this latter adjusting means need not provide for other than a relatively small amount of adjustment or compensation in the positioning of the frames.

It is to be understood that by the term "looped means" it is not necessarily to be inferred that the looped or hooked end of the ultimate connecting piece is formed into a complete or closed loop. In some instances and with some particular harness mechanisms hooks are preferably to be used while in other instances complete or closed loops may be preferred. In any event, the term is to be understood as embracing both hooks and other forms of mechanism which may be classed as looped structures.

The threaded connection between the shank 33 and the sleeve 29 should in some manner provide for locking the parts so that the looped connectors do not rotate once they have been adjusted to proper position. One expedient which has been found to suffice is that of bending the shank 33 and its threaded end slightly so that it flexes somewhat when it is screwed into the

sleeve. If the threads are thus caused to bind slightly, it has been found that there is no tendency for the parts to become unscrewed. If desired a lock nut may be used.

Now referring to Fig. 3, a modification of the invention is comprised of two opposed clamp members 35, these being similar to the members 21 and 22, Fig. 2. Instead of using a threaded sleeve such as the sleeve 29 it may be simpler and cheaper to employ a looped member having an outer hook or loop 36, and a stem or shank 37, the latter being upset or otherwise formed with an enlarged abutment 38 at its lower end. This abutment 38 may have flattened sides just as in the case of the flange or abutment 30 and these flattened sides fit within recesses 39 which serve the same purpose as the recesses 32, Fig. 2. Here there is no adjustment possible, but it is to be understood that in practically all instances a relatively wide range of adjustment is provided within the harness mechanism itself such as adjustment by various turnbuckles or other expedients well known to those skilled in the art.

The modification as just above described is relatively simple and comprises only three parts per attaching unit, two of these parts being identical so that in manufacture only two different parts need be fabricated, it being understood that the screws or other connecting means by which the two clamping members are fixed in position are a standard connecting means purchasable in the open market.

While the invention has been described by reference to disclosure of more or less specific forms thereof, it is to be understood that the actual shape and size of parts may vary for different installations, and that other interconnecting means than the screws 24 may be used. In some instances it may be more desirable to employ clamping devices not dependent upon threaded engagement, and the invention is to be understood to contemplate the employment of such.

The sleeves 29 are preferably formed as separate members which are to be clamped in position as the assembly is fixed to the beaded rib of a harness frame upon which it is to serve. In some instances it may be preferred to thread the actual groove or vertical opening in the parts, that is, the two clamp members may be fixed together temporarily, drilled vertically and then tapped for the combination of the threaded shank of the looped connecting means. In another case it may be found more desirable to make the parts as in Fig. 3, the recesses 39 providing for some form of abutment or upset flange at the end of the shank 37, but it is not absolutely essential that the sides of the abutment be flattened to prevent rotation since with this simplified form of connecting means slight rotation of the looped connecting means may be permitted, but the parts may not rotate to any great extent any way.

While one preferred embodiment and one modification of the invention have been disclosed, it is to be understood that the inventive concept may be carried out in a number of ways. The invention is, therefore, not to be limited to the precise details described, but is intended to embrace all variations and modifications thereof falling within the spirit of the invention and the scope of the claims.

I claim:

1. For a loom harness frame having top and bottom rails the outer portions of which terminate in beaded longitudinal ribs, a harness

connecting means which comprises opposed clamp members, grooves in said clamp members for embracing the beaded rib of the frame and indentations disposed intermediate the ends of said grooves, an attaching means held by said clamp members comprising a looped end, a shank and means comprising an enlarged abutment forming a functionally integral portion of said shank and engageable between indentations in the clamp members for preventing its withdrawal from the clamp members and means for retaining said members in tight engagement with said beaded rib and for retaining the shank and that means functioning therewith to prevent its withdrawal from the clamp members.

2. For a loom harness frame having top and bottom rails the outer portions of which terminate in beaded longitudinal ribs, a harness connecting means which comprises opposed clamp members, complementary rib bead engaging surfaces in said members, a looped harness attaching means comprising a looped end, a shank and an enlarged abutment forming a part of the end of the shank, complementary indentations in said clamp members for receiving said shank and enlarged abutment, and interconnecting means for said clamp members by means of which they are drawn into clamping engagement with both the beaded rib of the frame and the shank and abutment of the looped attaching means.

3. For a loom harness frame having top and bottom rails the outer portions of which terminate in beaded longitudinal ribs, a harness connecting means which comprises opposed clamp members, grooves in said clamp members for embracing the beaded rib of the frame, a looped harness attaching means comprising a shank with a loop at one end and an enlarged shouldered abutment at the other end, the sides of said shouldered abutment being flattened, complementary grooves in said clamp members for receiving the shank of the attaching means, recesses in said members at the base of the grooves for the shank which provide a stop means for preventing removal of the shank and further cooperate with the flattened sides of the abutment to restrain it against rotation in the members, and means passing through the clamp members for drawing them into clamping engagement with both the beaded rib of the frame and the shank and abutment of the looped attaching means.

4. For a loom harness frame having top and bottom rails the outer portions of which terminate in beaded longitudinal ribs, a harness connecting means which comprises opposed clamp members, grooves in said clamp members for embracing the beaded rib of the frame, an attaching means comprising a threaded sleeve and a looped bolt threaded into said sleeve, said sleeve comprising a cylindrical portion and shouldered abutment, grooves in said clamp members for receiving said cylindrical portion of the sleeve and recesses at the base of the grooves for receiving said abutment and preventing withdrawal of the sleeve and looped bolt from the clamp members after said clamp members have been firmly attached to the beaded rib of a frame.

5. For a loom harness frame having top and bottom rails the outer portions of which terminate in beaded longitudinal ribs, a harness connecting means which comprises opposed clamp members, grooves in said clamp members for embracing the beaded rib of the frame, an attaching means comprising a threaded sleeve and

a looped bolt threaded into said sleeve, said sleeve comprising a cylindrical portion and a shouldered abutment, the side of said abutment being flattened, grooves in said clamp members for said cylindrical portion of the sleeve and recesses at the base of the grooves for receiving said abutment, said recesses serving to prevent withdrawal of the sleeve and in cooperation with the flattened sides of the abutment to prevent rotation thereof in the clamp members when the latter are drawn into clamping engagement, and screw means for drawing said members into engagement with the beaded rib of the frame and with the sleeve.

15 6. Mechanism as defined in claim 5 wherein said screw means are threaded into the clamp means, one from one side and one from the other, thereby to make possible the use of identical parts for each member.

20 7. For a loom harness frame having top and bottom rails the outer portions of which terminate in beaded longitudinal ribs, a harness connecting means which comprises opposed clamp members, grooves in said clamp members for embracing the beaded rib of a frame, other grooves forming a part of said clamp members and being directed at right angles to said first mentioned grooves, an attaching means comprising an internally threaded sleeve and a looped bolt threaded into said sleeve, said sleeve being received within said other grooves and further having a shouldered abutment at the end opposite the loop of the bolt and complementary shouldered portions forming a part of said clamp members against which said abutment bears for preventing axial withdrawal of the sleeve when the parts are assembled.

35 8. For a loom harness frame having top and bottom rails the outer portions of which terminate in beaded longitudinal ribs, a harness connecting means which comprises opposed clamp members, grooves in said clamp members for embracing the beaded rib of a frame, other grooves forming a part of said clamp members and being directed at right angles to said first mentioned grooves, an attaching means comprising an internally threaded sleeve and a looped bolt threaded into said sleeve, said sleeve being received within said other grooves, and means for preventing withdrawal of said attaching means from said clamp members when the parts have been assembled which includes an abutment on said sleeve and complementary surfaces forming a part of said clamp members against which said abutment bears.

40 9. For a loom harness frame having top and bottom rails the outer portions of which terminate in beaded longitudinal ribs, a harness connecting means which comprises opposed clamp members, grooves in said clamp members for embracing the beaded rib of a frame, other grooves forming a part of said clamp members and being directed at right angles to said first mentioned grooves, an attaching means adapted to be clamped within said other grooves and including a looped member extending between said other grooves, an abutment forming a functionally integral part of said looped member and complementary surfaces formed in said clamp members against which said abutment bears.

45 10. For a loom harness frame having top and bottom rails the outer portions of which terminate in beaded longitudinal ribs, a harness connecting means which comprises opposed clamp members, complementary rib bead engaging sur-

faces in said members, a looped harness attaching means, cooperating grooves in said clamp members disposed at right angles to the bead engaging surfaces, said grooves being of such size and extent as to restrain a portion of said looped attaching means, and complementary interengaging means forming parts of the clamp members and of the looped attaching means for preventing withdrawal of the latter from the former when the clamp means are attached to a beaded rib of a harness frame.
